TAB REMOVING TOOL FOR USE WITH PRINTING AND LIKE DEVICES

Lester F. Mitchell, Shaker Heights, Ohio, assignor to Addressograph-Multigraph Corporation, Wilmington, Del., a corporation of Delaware

Application October 22, 1953, Serial No. 387,558

9 Claims. (Cl. 101—1)

This invention relates to a tool for use with indexing means of the kind employed on printing or printing and control devices or the like for the purpose of imparting particularity thereto.

Printing devices of the kind disclosed in Gollwitzer Reissue Patent No. Re. 22,249, patented January 12, 1943, or Hueber Patent No. 2,425,323, patented August 12, 1947, or printing and control devices of the kind disclosed in Gollwitzer Patent No. 2,132,412, patented October 28, 1938, customarily have associated therewith so-called indexing means in the form of detachable tabs that are adapted to extend beyond an edge of such a device, each such tab including a portion that is secured in retaining means in the form of a socket provided in the body of the carrier of the printing device adjacent to the edge thereof beyond which a portion of the tab is adapted to extend. Printing and printing and control devices of the aforesaid character are passed through machines equipped with sensing means adapted to cooperate with the tabs and which regulate the operation of operative elements in the machine in accordance with the particularities of the printing devices that are imparted thereto by the selected positions of the tabs thereon. It is essential that indexing means of this nature be firmly retained in position so as to insure against displacement thereof in the course of passage of the devices through machines of the aforesaid character or in other handling thereof, and resultantly resort has been advantageously had to an index tab of the kind disclosed in Gollwitzer Patent No. 2,049,439, patented August 4, 1936. A tab of this kind includes a body portion that is adapted to extend beyond the edge of the printing or printing and control device to which it is attached, and the tab also includes a stem portion extended from one edge of the body portion and which is adapted to be inserted selectively into retaining means, commonly referred to as sockets, provided in the body of the carrier of the printing or printing and control device, retaining means of this nature being disclosed in the patent to Gollwitzer No. 2,049,436, patented August 4, 1936, such retaining means being particularly adapted for cooperation with tabs of the kind disclosed in aforesaid Patent No. 2,049,439.

The stem portion of a tab of the aforesaid character includes a yieldable tongue that is normally disposed in the plane of the stem but which is so arranged that when the stem portion of the tab is inserted into a socket of the kind disclosed in aforesaid Patent No. 2,049,436, camming means, that are a part of the socket, act on such a tongue to force the same out of the plane of the stem to thereby bring the free end portion of the tongue into position to engage an edge of a panel that is a part of the socket arrangement, such end of the tongue engaging such edge of the panel when the stem portion of the tab is fully inserted into the socket therefor. This is effective to prevent displacement of the tab from the socket unless and until the yieldable tongue is depressed to disengage the free end thereof from the aforesaid edge of the panel.

2

When, however, the tongue is so depressed the tab may be freely withdrawn from the socket, but until the tongue is so depressed the tongue remains in retaining position and the tab is firmly held in the desired position on the 5 printing or printing and control or like device.

The yieldable tongues that are provided on the stems of tabs on indexing means of the aforesaid character are necessarily of restricted size, and while such tongues may be depressed by engaging a fingernail therewith, it is advantageous to provide manipulative means for depressing the tongue. The manipulative means that have been proposed heretofore have been relatively expensive and it is therefore the primary object of this invention to provide manipulative means in the form of a tool that will be 10 relatively inexpensive but which will, nevertheless, be effective, upon proper manipulation thereof, to depress a yieldable tongue of the aforesaid nature so as to facilitate detachment of the tab of which the tongue is a part from the retaining means in which it has been secured. 15 20 Printing and printing and control devices of the aforesaid nature are of predetermined and uniform size, especially insofar as particular styles thereof may be concerned, this being necessitated by the design of elements in the machines through which the devices are passed that 25 are to cooperate with the devices in the course of passage thereof through the machines. It is, therefore, another important object of this invention to provide manipulative means in the form of a detachment tool of such nature that a device of the aforesaid character may be inserted 30 thereinto in such a way as to facilitate proper orientation of means on the tool with the depressible tongue of a tab mounted on the device so that depression of the tongue will be effected upon subsequent manipulation of the tool, and an object related to the foregoing is to so arrange 35 a tool of the aforesaid character that it will embody means of the aforesaid character that will cooperate with the yieldable tongue of a tab in at least selected ones of the various positions at which a tab may be mounted on a printing or printing and control device or the like. 40 Other and more specific objects of this invention are to form a tool of the aforesaid character from relatively rigid but yieldable material; to so form the tool that insertion of a printing or printing and control device thereinto may be expeditiously effected; to so arrange the tool that 45 indicia may be provided thereon which will facilitate identification of the positions on a printing or printing and control device whereat indexing means in the form of a tab of the aforesaid means may be selectively secured, and to provide a novel tool of the aforesaid character that 50 will be of simple and economical construction and yet efficient and positive in operation.

Other and further objects of the present invention will be apparent from the following description and claims and are illustrated in the accompanying drawing which, by way of illustration, shows a preferred embodiment of the present invention and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

Fig. 1 is a perspective view of a tool embodying the present invention;

Fig. 2 is a fragmentary rear elevational view of a printing device equipped with indexing means of the kind with which the tool of this invention is adapted to be employed;

Fig. 3 is a transverse sectional view taken substantially on the line 3—3 on Fig. 1;

Fig. 4 is a fragmentary horizontal sectional view showing the manner in which the tool is arranged to cooperate with yieldable tongues on indexing means secured at various positions along an edge of a printing or printing and control device, and which view is taken substantially along the line 4—4 on Fig. 5;

Fig. 5 is a fragmentary vertical sectional view through an indexing means in the form of a tab of the aforesaid character and the body of the printing or printing and control device to which the tab is secured, and also showing the tool of the present invention in position to cooperate with the yieldable tongue on such a tab;

Fig. 6 is a top plan view of the tool shown in Fig. 1;

Fig. 7 is a rear elevational view of the tool and wherein portions of a printing or printing and control device with which it is to be used are shown in broken lines so as to illustrate the manner in which the novel tool of this invention is associated with such a device; and

Fig. 8 is a sectional view of a printing or printing and control device taken substantially in the same position as that in which Fig. 5 is taken and showing the tool of this invention associated with the device and illustrating the manner in which the tool is manipulated to facilitate removal of an index tab from a socket or retaining means in which it is secured.

In the accompanying drawing a printing and control device D of the aforesaid nature is illustrated which includes a carrier C, the end portions of which are folded upon themselves to provide spacing flanges as SF which project beyond the rear face of the carrier C and which serve to space the devices one from the other in the drawers or the like in which such devices are customarily stored when not in use and on which the devices travel during course of passage thereof through the machine. Retaining lips as RL are struck up from the face of the carrier C and cooperate with a bead UB formed along the upper edge of the carrier to retain a card as CA on the carrier C along the upper edge thereof. Other retaining devices RLP cooperate with a bead LB formed along the lower edge of the carrier C to retain a printing plate P on the face of the carrier C. Type characters (not shown) are customarily embossed on the plate P to have impressions made therefrom when a printing device D including such a plate is passed through a suitable printing machine. Customarily an impression from at least selected ones of such type characters is made on a card as CA to facilitate identification of the printing device D of which such a plate and a card are elements. The illustrated and described printing device is illustrative of a wide variety of such devices which, as is well understood in the art, may have one or more cards as CA secured thereto and which may also carry one or more printing plates as P.

Along what is customarily referred to as the upper edge of the carrier C, a plurality of sockets generally indicated by S are provided. Each of these sockets includes a panel PA that is offset from the body of the carrier C on the rear face thereof and which desirably is arranged in parallel relation with the body of the carrier C. Inwardly of each panel PA, each socket includes an inclined panel IPA which is offset from the body of the carrier C on the rear face thereof but which is arranged in inclined relation with the body of the carrier to define an opening O aligned with the passage between the panel PA and the body of the carrier C. Desirably a plurality of sockets as S are provided on each carrier C and customarily twelve such sockets are provided so that a tab as T may be mounted in any one or more of twelve positions along an edge of a printing or printing and control device as D.

Each tab as T includes a substantially rectangular body portion of which the greater portion is adapted to extend beyond the edge of a carrier C when a tab is secured in a socket as S, such extension of a portion of the body of a tab being shown in Fig. 2. Each tab as

T also includes a stem portion as ST which is narrower than the narrowest dimension of the rectangular body portion of the tab and which projects from one of the narrower edges of the body of the tab. Each stem portion is equipped with a yieldable tongue as YT that normally lies in the plane of the stem ST. When, however, the stem portion ST of the tab as T is inserted into a socket as S, the leading edge of the stem portion ST first passes under the panel PA and then enters the opening O and moves along the inner inclined face of the panel IPA so that when the tab is properly inserted in the socket, as shown in Fig. 5, the free end portion of the stem ST is inclined out of the normal plane thereof. Such inclination of this end portion of the stem of the tab and the edge E of the opening O is effective to cam the yieldable tongue YT out of the plane of the stem ST, and when the tab is fully inserted the free edge of this yieldable tongue is disposed behind the lower edge of the panel PA with which it cooperates to prevent withdrawal or accidental displacement of the tab T from the socket S in which it is so mounted. In order to remove a tab as T from a socket as S it is necessary to so depress the yieldable tongue as YT that the free edge thereof is moved out of alignment with the lower edge of the panel PA and when this is done the tab may be withdrawn and immediately after slight outward movement of the tab T from a socket S the tongue as YT may ride along on the inner surface of the panel PA and, when the tab is fully withdrawn from the socket, all parts thereof are free to resume their normal positions.

As can be ascertained by reference to Fig. 2, the yieldable tongues as YT are of restricted size, and it is therefore advantageous to provide manipulative means to facilitate depression thereof to enable withdrawal of a tab as T from a socket as S, and the detaching tool of the present invention is arranged to facilitate such depression of a yieldable tongue as YT.

While the tool of the present invention may be made from a wide variety of materials, I prefer to form the same from a thermoplastic material such as a cellulose acetate, polystyrene or kindred synthetic resinous material for so to do imparts the desired resiliency to the tool and enables the same to be of relatively light weight and otherwise facilitates handling thereof. The tool is formed by folding a substantially rectangular sheet of thermoplastic material or the like upon itself to provide substantial parallel but spaced-apart walls as 10 and 11 interconnected by a substantially U-shaped bight portion 12. Desirably, the wall 10 is of greater extent than the wall 11 and the wall 11 is desirably slightly inclined toward the wall 10 but remains spaced therefrom whereby a space or pocket is afforded into which a printing or printing control or like device may be inserted. In order to facilitate such insertion of such a device, a flange 13 is afforded along the free edge of the wall 11 and the flange 13 is inclined away from the wall 10 so as to thereby afford a relatively wire throat leading to the pocket into which a device as D is to be inserted.

As best shown in Figs. 1 and 7, the upper portions of the side edges of the walls 10 and 11 are slightly inclined inwardly so that the portions 14 and 15 of the side edges of the walls adjacent to the bight portion 12 are straight. As best shown in Fig. 7, the edges 14 and 15 of the walls of the tool are spaced one from the other in such a degree as to enable the portions 14 and 15 to be neatly fitted between the inwardly disposed faces of the spacing flanges as SF provided on a printing or printing control or like device as D. As stated hereinabove, such devices are of uniform size, especially insofar as particular styles may be concerned, and it will be understood that the space between edges as 14 and 15 will be related to the space afforded between the inner surface of spacing flanges as SF on the particular device with which my novel tool is to be employed. Hence, when a device as D is inserted into the pocket between the walls 10 and 11, the edges

14 and 15 cooperate with adjacent faces of the spacing flanges as SF on the inserted device as D to prevent endwise displacement of the device from the tool and this also facilitates proper orientation of the device in the tool, as will be explained.

In the portion of the wall 10, extended beyond the flange 13 and adjacent to the upper free edge of this wall, one or more protuberances as 16 are formed to extend inwardly of the wall. Where a device as D with which my novel tool is adapted to be used includes twelve sockets as S, it is advantageous to provide a corresponding number of protuberances 16. Furthermore, the protuberances as 16 are aligned one with the other across the wall as 10. Yet further, the protuberances as 16 are spaced from the bight portion 12 to such an extent that when the lower edge of a device as D, with which my novel tool is designed to be used, is inserted between the walls 10 and 11 and engaged with the inner surface of the bight 12, the projections as 16 will be respectively aligned with the sockets S and also in alignment with the yieldable tongue as YT on tabs as T selectively inserted into the sockets as S on the particular device. Therefore, when a device as D has been inserted between the walls 10 and 11 and the lower edge thereof engages the inner surface of the bight portion as 12 and the edges 14 and 15 on the tool respectively cooperate with the adjacent faces of the spacing flanges SF on the device, the assembled elements may be grasped in the hand, as shown in Fig. 8, and by applying pressure to the outer face of the wall 10 adjacent to a particular protuberance 16, such protuberance may be forced down into engagement with the underlying yieldable tongue YT which, upon the application of sufficient pressure, will be bent toward the body of the carrier C so that the free end of this particular tongue will be moved out of alignment with the inner edge of the panel PA of the socket S in which the particular tab is inserted and thereupon the tab as T may be freely withdrawn from the socket. Upon release of the pressure effective to so depress a yieldable tongue as YT, the printing device D may be freely withdrawn from my novel tool.

It has been explained that the devices as D customarily have twelve sockets as S provided therein so as to thereby afford accommodation for twelve tabs as T. Thus, one or more tabs as T may be selectively secured in the sockets as S in the printing device as D for the purpose of imparting particularity thereto, which is to say, for the purpose of classifying the device and when the entire exposed portion of a tab as T is utilized for this purpose, twelve primary classifications are afforded.

However, by cutting away a portion of the exposed portion of each tab so that one-half of each tab may afford a primary selection, the number of primary selections that is afforded is increased to twenty-four where twelve tab sockets are provided as is explained in Duncan Patent No. 1,082,505, patented December 30, 1913. Furthermore, by providing an embossure at any one of four different positions on the exposed portion of a tab, in an instance where twelve sockets are provided, it is possible to afford forty-eight primary selections, an arrangement of this character being disclosed in the patent to Gollwitzer 1,930,799, patented October 17, 1933.

In the patent to Hueber No. 2,359,851, patented October 10, 1944, a printing machine is disclosed which embodies what is called a selector arrangement that is adapted to cooperate with indexing or classifying means in the form of tabs on printing devices for the purpose of controlling the functioning of operative elements in the machine. This patent discloses a selector which may be arranged to cooperate with tabs arranged to afford twelve, twenty-four or forty-eight primary selections, as described hereinabove, and this patent also discloses an arrangement wherein by selectively forming a perforation at one of five different positions in the exposed portion of a tab,

any instance where twelve tab sockets are provided, the number of primary selections may be increased to sixty. It is also explained in the aforesaid Patent No. 2,359,851, that whether resort is to be had to an arrangement affording twelve, twenty-four, forty-eight and sixty primary selections, that by disposing properly arranged tabs in various of the sockets a wide variety of secondary or subordinate classifications may be afforded.

It has been customary heretofore to number the positions at which tabs may be selectively attached to a device as D so as to thereby facilitate insertion of the tabs in position to afford a particular primary or subordinate classification as may be desired. Heretofore, this has been done by engraving or otherwise forming numerals on the rear face of the carrier C of a device as D but because of the relatively limited area on the particular device where such numerals could be afforded in association with the sockets to indicate the primary selecting positions, it has sometimes been somewhat difficult to read the numbers provided on a particular device.

In view of the foregoing, the novel tool of the present invention is not only arranged in the manner described hereinabove so as to facilitate removal of an index or classification tab as T from a device as D but the device is also arranged to include indicia indicative of the positions at which primary selections may be afforded on a device as D when resort is had to one or the other of the arrangements of the exposed portion of a tab as T that have been explained hereinabove.

Thus, it has been explained that each protuberance as 16 is arranged for alignment with a tab receiving socket as S on a particular device as D with which the tool is to be used. Consequently, by scoring or imprinting the exposed face of the wall 10 panels as 17 may be defined thereon. Numerical indica as 18 may then be provided in each panel 17 to indicate the numbers of the positions at which primary selections can be afforded by inserting a tab into the socket as S on the device as D aligned with a particular protuberance and the panel associated therewith when a device as D is inserted into the novel tool of the present invention in a manner described hereinabove.

Thus, by referring to Fig. 1, it will be noted that the numerals 1 to 12 are respectively afforded in the panels 17 associated with the respective protuberance as 16, such numerals being engraved or imprinted at an appropriate position in the panel. These numerals 1 to 12 serve to numerically designate the twelve primary selections that may be afforded when resort is had to full tabs as T for the purpose of imparting particularity to a device as D to classify the same.

Since resort may be had to cut away tabs such as are disclosed in aforesaid Patent No. 1,082,505, which are so-called half-tabs, and which afford twenty-four primary selections where twelve tab sockets are provided. The numerals 13 to 24 are provided in the aforesaid panels respectively in association with the numerals 1 to 12. This numerical indica may be afforded on the wall 10 in the same manner as that described hereinabove and this numerical indica identifies the twenty-four positions at which so-called half-tabs may be selectively mounted to afford any one of the twenty-four primary selections afforded by such tabs.

The numerals 25 to 36 are also afforded in the panels 17 respectively in the panels bearing the numerals 1 to 12 and this likewise applies to the numerals 37 to 48. By referring to the right-hand most panel 11, shown in Figs. 1 and 4, it will be noted that the numerals 1, 13, 25, and 37 are inscribed in the panel in such positions as to be indicative of the four positions at which embossures or openings may be formed on the exposed body of a tab as shown in aforesaid Patent No. 1,930,799. Moreover, the numerals 49 to 60 are suitably afforded in the respective panels 17 at what may be called a middle position to be indicative of the positions at which holes may

be formed in the center of the exposed portion of a tab and whereat a perforation may be afforded to impart a primary selection.

Thus, it will be seen that suitable indicia may be incorporated on the novel tool of this invention so as to render the same useful when tabs or other indexing means are to be associated therewith to indicate the positions at which as many as sixty different primary classifications may be afforded on a particular device as D. The wall of my device whereat such indicia may be provided affords a relatively large area so that the numerical indicia may be provided thereon in sufficient size as to enable facile reading thereof and this of course expedites the attachment of indexing or classification means to devices as D.

It will be manifest from the foregoing description that I have provided a novel tool which may be employed in aligning indexing means such as tabs on printing, printing control or like devices. Where such indexing means include yieldable tongues operative to effectively retain the indexing means on the device, my novel tool may be employed to expeditiously retract such tongues from retaining position whereby removal of the indexing means from the device is facilitated. It will, therefore, be apparent that I have provided a tool which enables the hereinabove set forth and kindred objects of this invention to be realized.

Moreover, while I have illustrated and described the preferred embodiment of my invention, it is to be understood that this is capable of variation and modification, and I therefore do not wish to be limited to the precise details set forth, but desire to avail myself of such changes and alterations as fall within the purview of the following claims.

I claim:

1. A tool of the kind described formed from a substantially rectangular sheet of thermoplastic material folded upon itself to afford substantially parallel and spaced apart walls interconnected at corresponding ends thereof by a substantially U-shaped bight portion to define a pocket into which a printing, printing and control or like device may be inserted, one of said walls having an outwardly inclined flange along the free edge thereof to provide a throat leading to said pocket; and a plurality of spaced apart protuberances formed on a face of the other of said walls adjacent to a free edge thereof and extended inwardly of said wall, each of said protuberances being effective, when pressed inwardly, to release a retaining means on a device of the aforesaid nature inserted into said pocket to have spaced apart retaining means thereon respectively aligned with said protuberances.

2. A tool of the kind described formed from a substantially rectangular sheet of thermoplastic material folded upon itself to afford substantially parallel and spaced apart walls interconnected at corresponding ends thereof by a substantially U-shaped bight portion to define a pocket into which a printing, printing and control or like device may be inserted, one of said walls having an outwardly inclined flange along the free edge thereof to provide a throat leading to said pocket, the other of said walls being extended beyond the free edges of said flange; portions of the side edges of said walls spaced from said bight portion being inclined inwardly to thereby foreshorten the free edges of the walls remote from said bight portion, and a plurality of spaced apart protuberances formed on a face of said other of said walls adjacent to said free edge thereof and extended inwardly of said wall, each of said protuberances being effective, when pressed inwardly, to release a retaining means on a device of the aforesaid nature inserted into said pocket to have spaced apart retaining means thereon respectively aligned with said protuberances.

3. A tool of the kind described formed from a substantially rectangular sheet of innately resilient material folded upon itself to afford substantially parallel and spaced apart walls interconnected at corresponding

ends thereof by a substantially U-shaped bight portion to define a pocket into which a printing, printing and control or like device may be inserted, one of said walls having an outwardly inclined flange formed along the free edge thereof remote from said bight portion to provide a throat leading to said pocket, the other of said walls being extended beyond the free edge of said flange; and a plurality of spaced apart protuberances formed on a face of said other wall adjacent to the free edge thereof remote from said bight portion and extended inwardly of said wall, each of said protuberances being effective, when pressed inwardly, to release a retaining means on a device of the aforesaid nature inserted into said pocket to have spaced apart retaining means thereon respectively aligned with said protuberances.

4. A tool adapted for use with a substantially flat rectangular printing, printing and control or like device of predetermined dimensions and which has projections extended beyond one of the faces thereof along opposite edges thereof and which device has indexing means secured thereto to project beyond an edge thereof extended between said opposite edges and which indexing means includes releasable retaining means for removably retaining the indexing means at predetermined positions along said edge of said device; said tool comprising substantially parallel walls interconnected along corresponding edges thereof by a substantially U-shaped bight portion to thereby define a pocket into which a device of the aforesaid character may be inserted, the side edges of at least one of said walls being spaced one from the other to an extent as to neatly fit between the inwardly disposed faces of the projections on a device of the aforesaid character inserted into said pocket, at least one of the walls of said tool being projected from said bight portion to such an extent as to have the marginal edge thereof disposed over the retaining means for indexing means secured to a device of the aforesaid character inserted into said pocket to have the edge of the device opposite that beyond which the indexing means project engaged with the inner surface of said bight portion, and at least one protuberance formed in said marginal portion of said wall to project inwardly thereof and which is positioned to be aligned with the releasable retaining means on index means on a device inserted as aforesaid whereby pressure applied to said wall to force said protuberance toward said retaining means will be effective to release said retaining means to thereby enable said index means to be detached from said device.

5. A tool adapted for use with a substantially flat rectangular printing, printing and control or like device of predetermined dimensions and which has projections extended beyond one of the faces thereof along opposite edges thereof and which device has indexing means secured thereto to project beyond an edge thereof extended between said opposite edges and which indexing means includes releasable retaining means for removably retaining the indexing means at predetermined positions along said edge of said device, such indexing means being formed and positioned along said edge of said device to impart a particular classification to the device, said tool comprising substantially parallel walls interconnected along corresponding edges thereof by a substantially U-shaped bight portion to thereby define a pocket into which a device of the aforesaid character may be inserted, the side edges of at least one of said walls being spaced one from the other to an extent as to neatly fit between the inwardly disposed faces of the projections on a device of the aforesaid character inserted into said pocket, at least one of the walls of said tool being projected from said bight portion to such an extent as to have the marginal edge thereof disposed over the retaining means for indexing means secured to a device of the aforesaid character inserted into said pocket to have the edge of the device opposite that beyond which the indexing means project engaged with the inner surface of said bight portion

tion, and at least one protuberance formed in said marginal portion of said wall to project inwardly thereof and which is positioned to be aligned with the releasable retaining means on index means on a device inserted as aforesaid whereby pressure applied to said wall to force said protuberance toward said retaining means will be effective to release said retaining means to thereby enable said index means to be detached from said device, the outer surface of the wall in which a protuberance is formed, as aforesaid, having indicia associated therewith to indicate the particular classification that may be imparted thereto by attaching indexing means having predetermined characteristics to said device in alignment with said protuberances and indicia.

6. A tool adapted for use with a substantially flat rectangular printing, printing and control or like device of predetermined dimensions and which has projections extended beyond one of the faces thereof along opposite edges thereof and which device has indexing means secured thereto to project beyond an edge thereof extended between said opposite edges and which indexing means includes releasable retaining means for removably retaining the indexing means at predetermined positions along said edge of said device, such indexing means being formed and positioned along said edge of said device to impart a particular classification to the device, said tool comprising substantially parallel walls interconnected along corresponding edges thereof by a substantially U-shaped bight portion to thereby define a pocket into which a device of the aforesaid character may be inserted, the side edges of at least one of said walls being spaced one from the other to such an extent as to neatly fit between the inwardly disposed faces of projections on a device of the aforesaid character inserted into said pocket, at least one of the walls of said tool including a marginal portion adapted to overlie the portion of a device of the aforesaid character whereat indexing means of the aforesaid character may be attached, the outer surface of said wall having indicia thereon disposed to indicate the position along said edge whereat indexing means of predetermined form may be secured to impart a particular classification to said device.

7. A tool of the kind described adapted for use with a substantially flat printing, printing and control, or like device having indexing means secured thereto adjacent one edge thereof, said indexing means including releasable retaining means, spaced from the opposite edge of the device by a predetermined distance, for removably retaining the indexing means at predetermined positions along the one edge of the device, said tool comprising a sheet of resilient material folded upon itself to afford substantially parallel spaced walls defining a pocket into which a device of the aforesaid character may be inserted, and a plurality of protuberances formed on a face of one of said walls adjacent a free edge thereof and extending inwardly of said wall, said protuberances being spaced from the bight portion of the tool by a distance substantially equal to said predetermined distance and effective, upon manipulation of the tool, to release said retaining means upon a device of the aforesaid character when the device is fully inserted into said pocket.

5 8. A tool of the kind described adapted for use with a substantially flat printing, printing and control, or like device having indexing means secured thereto adjacent one edge thereof, said indexing means including releasable retaining means, spaced from the opposite edge of the device by a predetermined distance, for removably retaining the indexing means at predetermined positions along the one edge of the device, said tool comprising a sheet of resilient material folded upon itself to afford a U-shaped structure having substantially parallel spaced walls defining a pocket into which a device of the aforesaid character may be inserted, and a plurality of protuberances formed on a face of one of said walls adjacent a free edge thereof and extending inwardly of said wall at positions corresponding to the positions of said retaining means on said device, said protuberances being spaced from the bight portion of the tool by a distance substantially equal to said predetermined distance and effective, when pressed inwardly, to release said retaining means upon a device of the aforesaid character when the device is fully inserted into said pocket.

10 9. A tool of the kind described adapted for use with a substantially flat printing, printing and control, or like device having indexing means secured thereto adjacent one edge thereof, said indexing means including releasable retaining means, spaced from the opposite edge of the device by a predetermined distance, for removably retaining the indexing means at predetermined positions along the one edge of the device, said tool comprising a substantially rectangular sheet of resilient material folded upon itself to afford a U-shaped structure having substantially parallel spaced walls defining a pocket into which a device of the aforesaid character may be inserted, one of said walls having an outwardly inclined flange

15 20 25 30 35 40 45

formed along the free edge thereof remote from the bight portion of said structure to provide a throat leading into said pocket, and a plurality of protuberances formed on a face of the other of said walls adjacent the free edge thereof and extending inwardly of said wall, said protuberances being spaced from the bight portion of the tool by a distance substantially equal to said predetermined distance and effective, when pressed inwardly, to release said retaining means upon a device of the aforesaid character when the device is fully inserted into said pocket.
